UNITED STATES PATENT OFFICE

99,392

DESIGN FOR A COAT

Maurice Hirsh, Chicago, Ill.

Application March 18, 1936, Serial No. 61,679

Term of patent 3½ years

To all whom it may concern:

Be it known that I, Maurice Hirsh, a citizen of the United States of America, residing in Chicago, county of Cook, and State of Illinois, have invented a new, original and ornamental Design for a Coat, of which the following is a specification, reference being had to the accompanying drawing, forming part thereof, wherein,

The characteristic feature of my design resides in the wide flaring lapel notched at the neckline and overlying the coat sleeve, as shown.

I claim:

The ornamental design for a coat, substantially as shown and described.

MAURICE HIRSH.
